METHOD OF TREATING HYDROCARBON OIL

William F. Moore, Bayside, N. Y., assignor to
Gasoline Products Company, Inc., Newark, N. J.,
a corporation of Delaware

Application November 28, 1932, Serial No. 644,608

1 Claim. (Cl. 196—48)

This invention relates to methods for converting higher boiling hydrocarbon oils into lower boiling hydrocarbon oils.

It is an object of my invention to provide an improved process for the separation of a heavy hydrocarbon oil charging stock into a plurality of fractions and for the treatment of these fractions in combination in such manner that increased conversion into the desired lower boiling point product results.

According to my invention a charging stock such as crude oil having a gravity of about thirty-five degrees A. P. I., or any other comparable product is heated to a moderate temperature under superatmospheric pressure and is thereafter introduced into an evaporating chamber wherein vaporization takes place and an unvaporized residue is formed. Vapors so produced are then heated to a relatively high cracking temperature and combined with the residue subsequent to the heating of the residue to a moderate cracking temperature. A dehydrogenating agent, such as oxygen, air or steam which has been superheated to dissociation temperature, may be mixed with the combined products to promote the formation of unsaturates and the combined products are thereupon introduced into a soaking chamber wherein further conversion and recombination takes place. The soaked products pass into a separating chamber, held under reduced pressure, wherein vapors are evolved and a tar-like residue formed. The vapors are thereafter subjected to partial condensation in a fractionator, and the uncondensed vapors are removed from the fractionator as the final desired product, while the condensate is combined with the vapors first mentioned, prior to the heating thereof. The residue produced in the separator is withdrawn from the process.

The above mentioned and further objects and advantages of my invention will be made clear in the following description taken in conjunction with the accompanying drawing.

In the drawing reference numeral 1 indicates a furnace having therein heating coils 2, 3, 4, and 5, which are subjected to heat produced by burners 6, 7, and 8. Nine (9) indicates an evaporator, 10 a soaking chamber, 11 a separator and 12 a fractionator. Fresh charging stock, such as for example as 35 degree A. P. I. M. C. crude, is forced by pump 30 through heating coil 2 positioned in the convection portion of the furnace, and then through heating coil 3 located in the radiant portion of the furnace. The heated oil products thereafter pass through pipe 13 and re-

ducing valve 14 into evaporator 9. The pressure in the heating coil may, for example, be 500 lbs. per square inch and the temperature to which the oil is heated therein may suitably be from 700°—850° F. preferably in the neighborhood of 750°—800° F. These conditions permit heating of the oil with substantially no cracking. The evaporator 9 may be carried under a pressure of 300 lbs. per square inch and this reduction in pressure of the heated oil introduced into the evaporator suffices to vaporize the lighter portions thereof, which may include gasoline, kerosene and gas oil, leaving a reduced crude residue of about 20 degrees A. P. I. gravity.

The vapors pass overhead through pipe 15 into a heating coil 4, and thence through injector 16 into soaking chamber 10. The temperature attained by the oil vapors in coil 4 may be from 950 degrees to 1200 degrees F. or even higher, but is preferably approximately 1050° F., while the pressure on the heated vapors leaving the coil will be relatively low, e. g. 150 pounds per square inch, although a somewhat lower or higher pressure may prevail. The residue from the evaporator is forced either by the pressure in the evaporator, or by pump 17, through heating coil 5 and injector 16, into the soaking chamber 10. The temperature attained by the residual oil in the coil 5 is preferably in the neighborhood of 850° F., but a slightly higher or lower temperature could be used if desired. The function of the injector 16, which may be of any well known type, is to combine and thoroughly mix the two streams of heated oil prior to their introduction into the soaking chamber. Other mixing means, such as an ordinary chamber may be used instead if desired. The pressure on the residual oil passed through the coil 5 may be made high enough by the action of pump 17, so that the heated residual oil can assist, through the action of the injector, in raising the pressure of the highly heated vaporous products prior to their introduction into the soaking chamber. A dehydrogenating agent such as oxygen, air or superheated dissociated steam may be introduced through pipe 18 into the injector 16 and mixed with the oil to promote polymerization and the formation of unsaturated hydrocarbon compounds.

The fractions of the vapors from evaporator 9 which lie in the gasoline boiling range may be removed in order to prevent the passage thereof through the heating coil 4, and in this event the temperature of the products passing through heating coil 4 may be increased to a value above

that mentioned hereinbefore, for example to 1500° F. Fractionator 39 which is provided to remove the gasoline boiling range fraction may be rendered active by proper manipulation of valves 40, 41, 42 and 43. When valve 40 is closed and valves 41, 42, and 43 are open the products enter the fractionator through pipe 44 and are fractionated therein, the lightest products passing off through line 45 which connects with the pipe 15 leading to the cracking coils. The heavy condensate is removed from the bottom of the fractionator through line 46 and introduced into pipe 15, while an intermediate cut of products in the gasoline boiling range is removed as a side stream through pipe 47 and is introduced into storage drum 48. Pipe line 49 having valve 50 is provided for by-passing the reflux condensate from pipe 23 around the fractionator 39, when the latter is in use and valve 51 serves to prevent the 20 reflux condensate from combining with the vapors from the evaporator when the by-pass line is in use.

The temperature of the combined products entering the soaking chamber will be intermediate 25 that of the heated residual products and that of the heated vapors, the highly heated vapors serving to raise the temperature of the residual products above that which they attain in the furnace. After being soaked in chamber 10 in which combination of the relatively light vapors and fixed 30 gases, with the heavy residual products occurs as a result of their unsaturated condition the products are transferred to separator 11 through a pipe 19 having a reducing valve 20 therein. The 35 pressure in the separator 11 is lower than that of the soaking chamber 10, for example the pressure in the separator may be 50 pounds per square inch. Lighter products in vapor form pass from the separator through conduit 21 into fractionator 12, while a liquid residue is withdrawn 40 through valve line 22. In the fractionator the vapors are dephlegmated, a reflux condensate being formed which is removed from the bottom of the fractionator through pipe 23 having pump 24 45 and is combined with the vapors in pipe 15 for heating in the coil 4. A cooling coil 38 is positioned in the top of the fractionator to supply the necessary refluxing action. The fresh charge may be passed through the coil if desired, in the usual manner. A connection 31 having a valve 50 50 therein is furnished for permitting a quantity of the reflux condensate from line 23 to be directed into evaporator 9 to control the conditions therein and regulate the proportion of vapors to residue 55 produced by the vaporizing process, as well as the quality of the residue. By regulating the valve 32, a greater or lesser amount of reflux condensate may be admitted. A pipe line 33 having valve 34 and cooler 35 serves to conduct any desired quantity 60 of cool reflux condensate into the separator to regulate the amount of vapors evolved therein. A valved by-pass 36 is included for passing hot condensate around the cooler, thereby affording additional flexibility of control. Valved drawoff line 37 affords a means for diverting from the process certain amounts of reflux condensate if desired.

Vapors of the desired end point leave the fractionator through conduit 25 and travel through condenser 26 into gas separator 27 wherein fixed 70 gas is drawn off in the usual manner through

pipe 28, and the desired final distillate is removed through pipe 29.

The pressures used in the process described hereinbefore may be increased if desired, the proper ratio of pressures being maintained. For 5 example a pressure of several thousand pounds per square inch may be placed on the fresh charging stock, and in this case the evaporator and soaking chamber should be held at proportionately lower pressures. The pressures on the 10 separator and fractionator may be raised also but generally pressures of from 50-400 pounds per square inch will be found preferable for the separating and fractionating steps.

By separating the crude petroleum charging 15 stock into two portions and treating them as described hereinbefore several desirable results are attained. Among these are the reformation of any gasoline content of the crude petroleum charging stock and the contacting of the resulting hot fixed gases and light products with the residue for further conversion and recombination, including polymerization. A further advantage is that more extensive cracking of the heavy oil can be obtained without coke difficulties than 25 would be possible in an externally heated coil alone. The two portions of the charging stock may also be subjected to individually controlled conditions which are especially well adapted for 30 their treatment.

While I have described a particular embodiment of my invention for the purpose of illustration it should be understood that various modifications and adaptations thereof may be made within the spirit of the invention as set forth in the appended 35 claim.

I claim:

In a process for the treatment of hydrocarbon oil wherein the oil is subjected to a topping operation for the separation of a low-boiling fraction, 40 containing materials within the boiling range of gasoline, from higher boiling residual components, said low-boiling fraction subjected to conversion conditions of elevated temperature and superatmospheric pressure in a heating coil and 45 communicating reaction chamber for the purpose of materially improving its motor fuel characteristics, particularly in respect to anti-knock value, without excessively altering the boiling range of gasoline constituents thereof, the vapor- 50 ous and residual conversion products separated, the vapors subjected to fractionation for the removal of their insufficiently converted high-boiling 55 fractions which are condensed as reflux condensate, fractionated vapors of the desired end-boiling point subjected to condensation and the resulting distillate and gas collected, the improvement which comprises commingling said reflux condensate and said high-boiling residual components and subjecting them to fractionation to 60 together for the separation of lighter constituents in vaporous form, and commingling the heavier constituents unvaporized in said fractionation with the heated oil from the heating coil, prior to the separation of vaporous and residual conversion products, whereby said heavier constituents are subjected to somewhat milder conversion 65 conditions than those employed in the heating coil.
